UNITED STATES PATENT OFFICE.

THOR RAUGSTAD, OF SANDNÆS, NEAR STAVANGER, NORWAY.

ROTARY ENGINE.

1,415,393.

Specification of Letters Patent.

Patented May 9, 1922.

Application filed August 26, 1921. Serial No. 495,529.

To all whom it may concern:

Be it known that I, THOR RAUGSTAD, a subject of the King of Norway, residing at Sandnæs, near Stavanger, Norway, have invented certain new and useful improvements in a Rotary Engine, (for which I have filed application in Norway Aug. 9, 1920, application No. 21,498;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object to provide a rotary engine adapted to be driven by liquid or gaseous medium (steam) and is also adapted to act as a pump by having its shaft driven from another source of power.

In the accompanying drawings, Figure 1 is a front view partly in section, of an engine embodying my invention:

Fig. 2, on the left hand side is a section on line A—B of Fig. 1 and on the right hand side partly a sectional view on line C—D and partly a side view of the engine.

The engine comprises a casing constituted by two side plates 19 forming a substantially circular chamber, the lower major portion of which has a uniform cross-sectional area while the upper or smaller portion has a gradually increasing cross-sectional area. On the engine shaft 10 which is journaled in the plates axially of the chamber, is fixed a rotor 11 which has a peripheral annular channel 12, preferably V-shaped in cross section, forming the pressure chamber of the engine. Mounted in the top of the casing and extending into the annular channel 12 is an abutment 13 conforming to the cross-sectional area of said channel.

A vane, operating in conjunction with the abutment, constitutes the driving element of the rotor. It consists of two blades 8, pivotally mounted on an axis 15 arranged on the rotor at right-angles to the axis of the latter, said blades being movable laterally into and out of the channel 12 through laterally arranged slots formed in the side walls of said channel and are adapted to open and close the latter as hereinafter described.

On one corner of each blade, adjacent the plates 19, is formed a trunnion 16 carrying an anti-friction roller 17 which runs in a

guide groove 18 formed in the inner face of each side plate 19 of the casing.

Steam or other pressure fluid is supplied to a chest 2 through an inlet pipe 1 said chest containing a slide valve 4 which controls a port 5 in an auxiliary slide 6, said port being connected by a passage 7 with the channel or pressure chamber 12 whereby the steam is supplied to the latter between the vane and the abutment. To permit of reversing the engine a chest of the structure just described is mounted on the casing on each side of the abutment and steam supplied through the inlet of one chest, for instance the inlet 1, will exhaust from the outlet 14 of the other chest located on the opposite side of the abutment 13. The exhaust or outlet ports 25 one of which is shown at the left side of Fig. 1, are controlled by the auxiliary slide valves 6. A lever 28 having a handle 27 is so connected to one auxiliary valve by the rods 29 and 30 and to the other auxiliary valve by rods 31 and 32 that said valves are simultaneously operated to close one port and open the other port.

Each slide valve 4 is operated from an eccentric 20 fixed on the engine shaft 10, said eccentric operating a pitman 21, connected to the arm 22 of a bell crank lever, the arm 23 of which is slidably connected to a rod 24 of said slide valve. The blades 8 of the vane are provided with fluid-tight packing strips 34 secured to the sides and outer end by any suitable means.

When operating the engine in one direction, the auxiliary slide valve 6 is in the position shown at the left side of Fig. 1, closing the outlet port 25 and channel 26, while the auxiliary slide valve in the other chest uncovers the outlet port of channel 14. Steam or other pressure medium entering inlet channel 1 passes into the channel or pressure chamber 12 between the left side of the abutment 13 and the vane, the blades of the latter being in position for closing the groove. As the vane approaches the right side of the abutment the blades are separated and moved out of the groove 12 by the trunnions 16 traveling in the grooves 18. The walls 19 of the casing are so formed that the grooves 18 cause the blades to be withdrawn from the channel 12 in approaching the abutment and to move back into the channel after passing the abutment.

To reverse the engine, the lever 27—28

is shifted to the left from the position shown in Fig. 1 so that the slide valve 6 closes port 5 and opens port 25 and channel 26. The slide valve in the chest at the right of the 5 abutment 13 is simultaneously shifted so that the port of inlet channel 33 is opened and the port of exhaust channel 14 is closed.

I claim—

1. A rotary engine comprising a casing, a 10 rotor journaled therein having a peripheral channel, a stationary abutment projecting into the latter, vane blades pivoted in the channel and movable transversely through lateral slots formed in the sides of the channel, the walls of the casing constituting guides for the blades to move the latter into and out of the channel during the movement of the rotor.

2. A rotary engine, comprising a rotor 20 having a peripheral channel, a stationary abutment projecting into the latter, vane blades pivoted in the channel and movable transversely through lateral slots formed in the sides of the channel, a casing enclosing 25 the rotor having side walls constituting guides for the blades to move the latter into and out of the channel during their movement in passing the abutment.

3. A rotary engine, comprising a casing 30 forming a chamber having a portion of uniform cross-sectional area and a portion of gradually increasing cross-sectional area, a rotor journaled in the casing having a peripheral channel, a stationary abutment

mounted in the casing at the point of largest 35 area and projecting into the channel, vane blades pivoted in the channel and movable transversely through lateral slots formed in the sides of the channel, trunnions formed on the blades projecting into guide grooves 40 formed in the walls of the casing whereby said blades are moved into and out of the channel during the movement of the rotor.

4. A rotary engine, comprising a casing 45 forming a chamber having a portion of uniform cross-sectional area and a portion of gradually increasing cross-sectional area, a rotor journaled in the casing having a peripheral channel, a stationary abutment mounted in the casing at the point of largest 50 area and projecting into the channel, vane blades pivoted in the channel and movable transversely through lateral slots formed in the sides of the channel, trunnions formed on the blades projecting into guide grooves 55 formed in the walls of the casing whereby said blades are moved into and out of the channel during the movement of the rotor, and means on opposite sides of the abutment for supplying pressure fluid to said channel. 60

In testimony that I claim the foregoing as my invention, I have signed my name in presence of two subscribing witnesses.

THOR RAUGSTAD.
